PISTON SKIRT EXPANDER

Filed March 6, 1939

INVENTOR:
CHARLES A. MARIEN,

UNITED STATES PATENT OFFICE

2,198,829

PISTON SKIRT EXPANDER

Charles A. Marien, St. Louis, Mo., assignor to
Ramsey Accessories Manufacturing Corporation,
St. Louis, Mo., a corporation of Missouri

Application March 6, 1939, Serial No. 259,963

6 Claims. (Cl. 309—12)

My invention has relation to improvements in expansion and tensioning devices for pistons, which devices are commonly called piston skirt expanders, and it consists of the novel features 5 of construction more fully set forth in the specification and pointed out in the claims.

The present invention is an improvement over that shown in Patent No. 1,806,416 granted to Harold F. Phillips and reissued as No. 18,653 on 10 November 15, 1932, and while it has the same general objects as those embodied in the Phillips patent, it embodies features of construction whereby it has a more universal application to pistons of different design than the Phillips construction, and it also embodies more reliable anchoring means.

The present expander also embodies structural features which insure that it will remain securely fixed in position within the skirt notwithstanding 20 the inertia and vibration to which it is subjected when the piston is traveling at extremely high speeds. The construction of my improved skirt expander is such that it automatically adapts itself while being fitted into the piston skirt to 25 variations and imperfections that occur in the general run of pistons. These features as well as others inherent in the invention will be better apparent from a detailed description of the same in connection with the accompanying drawing, 30 in which:

Figure 1 is a combination side elevation and middle vertical section taken through a conventional type of piston showing my improved skirt expander mounted on the piston pin and exerting its tension on the lower part of the piston skirt; Fig. 2 is a bottom plan of the piston showing the skirt expander secured therein; Fig. 3 is a vertical longitudinal section taken through the piston skirt on the line 3—3 of Fig. 1; Fig. 4 is an enlarged fragmentary view of the skirt expander showing in combined section and elevation the portion thereof where the expanding part of the expander and the supporting ear are joined together; Fig. 5 is a cross-sectional detail 45 taken on the line 5—5 of Fig. 4; Fig. 6 is a bottom plan of that portion of the expander shown in Fig. 4 showing in dotted lines the relative movement that is possible between the supporting ears and the expander proper in order to compensate for irregularities in the pistons, and thereby allow for lack of absolute parallelism of the faces of the piston pin bosses; Fig. 7 is a 50 combined side elevation and vertical longitudinal section on a reduced scale of a piston skirt showing a slightly different form of skirt expander

which has been dislodged from its initial position through the force of inertia and of the impact of the explosion during the operation of the engine: (this view is for comparison only with Fig. 1); and Fig. 8 is a side elevation on a reduced scale of a different type of piston having a solid non-slotted skirt.

Referring to the drawing, P represents a piston of a typical construction having its skirt 1 slotted at 2 immediately below the bottom ring land 3. 10 The skirt is also provided with a longitudinal slot 4 extending from slot 2 to the bottom of the piston skirt. Slot 4 is approximately midway between the piston pin bosses 5, 5 and, as well understood, is provided for the purpose of allowing the skirt to contract circumferentially to compensate for expansion caused by heat during the operation of the engine. Of course, in the case of cast iron or steel pistons these slots are generally not provided. Such a piston is 20 shown in Fig. 8, and the invention is in no wise dependent for its usefulness on a slotted piston. In order to restore to its proper shape a piston skirt that has been distorted or worn in use a piston skirt expander 6 is securely mounted with- 25 in the skirt.

My improved expander embodies an annular spring member 7 having parallel sides 8, 8 and arcuate skirt expanding parts 9, 9, separated by a gap 10, and 11 extending continuously from 30 one side 8 to the other. The general shape of the spring member 7 is similar to that shown in my Patent No. 1,887,769. However, in the present case the spring member 7 is secured within the skirt by a pair of oppositely disposed ears 35 12, 12 terminating in lobate members 13, 13, each of which is provided with an opening 14 for the reception of the piston pin 14'. The ears 12 terminate at their lower ends in three gripping fingers 15, 15 and 16 disposed therebetween, the 40 latter having a bead 17 extending inwardly for a purpose presently to appear. The spring member 6 and ears 12, 12 are maintained in assembled relation by forcing the sides 8, 8 within the oppositely disposed sets of fingers. 45

The central finger 16 on each side will of course yield so that the side 8 may pass beyond the crimp 17, after which this finger will snap together and member 8 be securely held within the finger. A slight clearance a is provided between 50 the base of the crimp 17 and the inner surface b of the side 8 so that the ear 12 may be capable of a lateral rocking movement as indicated by the dotted lines in Fig. 6. This lateral rocking movement allows for an automatic adjustment 55

of the lobate members 13, 13 so that they may fit snugly against the faces of the piston pin bosses 5, 5, even though the faces of these bosses may not be in absolute parallelism, as is often the case, not only in pistons that have been subjected to considerable use but also in the case of new pistons.

It will be observed (Figures 1 and 4) that the intermediate part 8' which receives the fingers 10 15, 15 and 16 is offset from the balance of the side member 8 so as to form shoulders s, s which serve as abutments for the outer edges of fingers 15, 15 and thus prevent movement of the ears 12, 12 on the side members 8, 8. Were it not for 15 this offset with its shoulders s, s the spring member 6 would be free to slide through the fingers 15, 15 and 16 and become displaced, as shown in Fig. 7, under the hammering action to which the piston is subjected during the operation of the 20 engine as alluded to above. However, due to the construction illustrated in Fig. 4 and just described, any tendency on the part of the spring member 6 to become displaced will be resisted by the ears 12, 12 so that the entire skirt expander assembly will remain rigidly in place under the most severe operating conditions.

In Fig. 8 I illustrate a piston P', the skirt of which is not slotted, as it is within the scope of the present invention.

30 Having described my invention, I claim:

1. A skirt expander for pistons having oppositely disposed piston pin bosses for the reception of a piston pin, said expander comprising an expanding part having side members and piston engaging members adapted to engage the opposite sides of the piston skirt intermediate of the bosses, and supporting members for said expanding part, said supporting members having fingers for gripping said side members and having lobate elements for the reception of the piston pin.

2. A skirt expander for pistons having oppositely disposed piston pin bosses for the reception of a piston pin, said expander comprising an

expanding part having side members and piston engaging members adapted to engage the opposite sides of the piston skirt intermediate of the bosses, and supporting members for said expanding part, said supporting members having fingers for gripping said side members and having lobate elements for the reception of the piston pin, and abutment means on the side members adapted to engage the supporting members.

3. A skirt expander for pistons having oppositely disposed piston pin bosses for the reception of a piston pin, said expander comprising an expanding part having side members and piston engaging members adapted to engage the opposite sides of the piston skirt intermediate of the bosses, and supporting members for said expanding part, said supporting members having fingers for gripping said side members and having lobate elements for the reception of the piston pin, and abutment means adapted for engagement with the supporting members.

4. A piston skirt expander comprising an expanding part and supporting members movably connected thereto, said supporting members having clamps for engaging the expanding part, and cooperating means on said members and expanding part holding the supporting members against movement lengthwise of the expanding part.

5. A piston skirt expander comprising an expanding part having side members and piston 30 engaging members, a supporting member movably secured to each of said side members, abutment means on each side member adapted for engagement with the adjacent edges of the supporting member.

6. A piston skirt expander comprising an expanding part for engagement with the piston skirt, and supporting members projecting upwardly from said expanding part, said supporting members having securing devices engaging the 40 expanding part, with clearance to permit automatic adjustment of the supporting members in the piston.

CHARLES A. MARIEN.
